UNITED STATES PATENT OFFICE.

JAMES E. MARGESON, OF JASPER, NEW YORK.

BARB-WIRE STRETCHER.

1,274,736.

Specification of Letters Patent.

Patented Aug. 6, 1918.

Application filed January 14, 1914. Serial No. 812,092.

To all whom it may concern:

Be it known that I, JAMES E. MARGESON, a citizen of the United States, residing at Jasper, in the county of Steuben, State of New York, have invented certain new and useful Improvements in Barb-Wire Stretchers; and I do hereby declare the following to be a full, clear, and exact description of the invention, such as will enable others skilled in the art to which it appertains to make and use the same.

This invention relates to improvements in wire working tools, and particularly to working tools especially adapted for stretching and splicing barb wire.

The principal object of the invention is to provide a simple device of this character which will be comparatively cheap to manufacture, and which will be effective in its operation to stretch barb wire and to repair broken wires by twisting the ends together.

Other objects and advantages will be apparent from the following description, when taken in connection with the accompanying drawings.

In the drawings:

Figure 1 is a perspective view showing the operation of the device when stretching the wire.

Fig. 2 is a longitudinal sectional view taken on the line 2—2 of Fig. 1.

Fig. 3 is a perspective view showing the device positioned to splice a broken wire.

Referring particularly to the accompanying drawings, 10 represents a handle which is slightly enlarged adjacent one end, as indicated at 11, and through this enlargement is formed an elongated slot or opening 12. Disposed through the enlargement and extending across the slot is a bolt 13 on which is pivotally mounted an outwardly extending arm 14. The outer end of this arm has the oppositely extending curved double-pointed claws 15. On the end of the shank adjacent the enlargement is detachably secured a hook-shaped plate 16.

Copies of this patent may be obtained for five cents each, by addressing the "Commissioner of Patents, Washington, D. C."

Referring particularly to Fig. 1, it will be seen that to stretch the barb wire 17, one of the claws 15 is caused to straddle the wire and engage against one of the barbs 18, after which the hook 16 is engaged on the opposite side of the post 19 and the lever swung with the hook 16 as the fulcrum. This will cause the claws 15 to pull against the barb 18 and stretch the wire across the face of the post so that the same may be quickly and easily attached by means of a staple.

When it is desired to splice a broken wire, the ends 20 of the broken wire are drawn so that their barbs engage with the claws 15 in a crossed manner, as clearly seen in Fig. 3. The enlargement 11 of the handle shank 10 is then grasped and used as a handle so as to turn the arm 14 and twist the ends 20 of the wire together. When the wire is sufficiently twisted, portions of the twisted ends can be cut off with the ordinary wire cutter.

From the foregoing it will readily be seen that I have provided a simple tool by means of which barb wires can be quickly and easily stretched, and by means of which broken wires can be easily spliced by twisting the broken ends together.

What is claimed is:

A device of the character described, comprising an arm bifurcated at one end with the furcations reversely bent to form a double-hook end portion providing gripping claws projecting from opposite sides of said arm, a lever pivotally supporting said arm for swinging movement, and a relatively wide fulcrum end on the lever for partially embracing a stationary support for the turning of the lever upon the latter.

In testimony whereof I affix my signature in the presence of two witnesses.

JAMES E. MARGESON.
